UNITED STATES PATENT OFFICE.

JOHN H. HENDRICKSON, OF CLEVELAND, OHIO, ASSIGNOR TO THE HENDRICKSON MACHINE COMPANY, OF CLEVELAND, OHIO.

GEARING FOR LAUNDRY MACHINERY.

1,347,221.

Specification of Letters Patent.

Patented July 20, 1920.

Application filed August 25, 1919. Serial No. 319,615.

To all whom it may concern:

Be it known that I, JOHN H. HENDRICKSON, a citizen of the United States, residing at Cleveland, in the county of Cuyahoga and State of Ohio, have invented certain new and useful Improvements in Gearing for Laundry Machinery, of which the following is a specification.

This invention relates to clothes washing-machines of the rotary cylinder type, and it has particular reference to the novel construction of the mechanism for operating the rotating cylinder and the wringer connected with the machine.

The primary object of the present invention is the provision of a simple, durable, economical, and convenient motor driven mechanism for revolving and automatically reversing, or oscillating the washing cylinder, and for operating the wringer in both directions of revolution of the rollers.

A further object is to provide simple means for shifting the wringer and coöperating mechanism to a number of positions, as desired, without disturbing the cylinder operating mechanism.

With these objects in view, the invention consists in the construction, combination and arrangement of parts as hereinafter described and set forth definitely in the appended claims, reference being had to the accompanying drawings which are made part of the specification, similar characters of reference being employed to designate corresponding parts.

In the said drawings Figure 1 is a side elevation of the improved machine.

Fig. 2 is an end elevation in direction of arrow *x*, Fig. 1, showing the body of the machine partially broken away.

Fig. 3 is a central vertical section on line 3—3, Fig. 5.

Fig. 4 is a fragmentary view in direction of arrow *x*, Fig. 1, with a portion of the gear housing broken away.

Fig. 5 is a plan view, and Fig. 6 is a section substantially on line 6—6 of Fig. 2.

Figs. 7, 8 and 9 are fragmentary views illustrative of a clutch operating means employed.

Referring now to the drawings, 1 represents a metallic tub supported by a frame structure 2, and having mounted therein, on a horizontal transverse axis, a rotatable cylinder 3, said cylinder being perforated and

provided with a sliding door 4. The design and arrangement of the elements thus far set forth are old in the art, and are not pertinent to the present invention, except as in combination with the improved mechanism.

In carrying out my improvement, which is adaptable to coöperation with the common elements above mentioned, a housing 5 is provided, which is rotatably mounted on a vertical bearing bracket 6, said bracket being firmly attached to the frame 2 so that the housing 5 can rotate above the top of the machine. A shelf 5^a is connected with the housing 5 and provides a support for the motor 7.

A vertical shaft 8 is journaled in the housing 5 and in the bracket 6, and has a worm wheel 9, keyed or otherwise secured thereto, in the upper part of the housing, as best shown in Fig. 3. The worm member 9 is the main driving element and is operated by an engaging worm 10 driven by the motor 7.

A pair of oppositely disposed bevel-gears 11 and 12 are carried by the shaft 8, said gears co-acting with a companion gear 13 on a horizontal shaft 14, to drive the wringer, the shaft 14 being connected with the lower wringer-roller 15. As there are several ways of connecting the said shaft and wringer-roller, that are common in shop practice, it is not deemed necessary to show said connection in detail. The oppositely disposed bevel-gears 11 and 12 in mesh with the gear 13 provide means for reversing the direction of revolution of the wringer rollers, through their co-action with clutch mechanism.

The said clutch mechanism includes a sleeve 16 mounted on the shaft 8 between the gears 11 and 12. Said sleeve is vertically slidable on a spline 8^a, and is provided with annular flanges 16^a and 16^b. A stub-shaft 17 is journaled in a boss 5^b, and carries an eccentric pin 17^a which operates on the flanges 16^a and 16^b. An operating handle 18 is attached to the shaft 17, said handle being provided with a projection 18^a which is adapted to engagement, respectively, in the grooves *a*, *b* and *c* in the face of the boss 5^b. When the handle is in the position shown in Figs. 4 and 7, the projection 18^a is in groove *a*, the sleeve 16 is in a neutral position, and the wringer is inoperative. It will be seen that the projection 110

may be withdrawn from engagement with groove *a* and the handle turned either to the right or left, as desired, the projection automatically engaging with either groove 5 *b* or *c*, as the case may be. When in engagement with groove *b* the eccentric pin 17^a causes the sleeve 16 to engage gear 11, and thus drive the wringer roll in one direction, and when engagement is made with groove 10 *c*, gear 12 is actuated, resulting in reversing the direction of revolution of said wringer rollers.

A bracket 19 is attached to the frame of the machine and connected with the bracket 15 6, as shown by the flanges 6^a and 19^a. A horizontal stub-shaft 20, journaled in said bracket 19, carries a bevel-gear 21, said gear being in mesh with a companion gear 22 on the lower end of the shaft 8. Provision is 20 made by the last named gears for driving the washing cylinder 3, through the novel combination and arrangement of elements as follows.

Mounted on the cylinder trunnion 23 is a 25 pinion 24. Said pinion normally is free on the trunnion, but is operatively connected therewith through the medium of the clutch 25 being actuated by a lever 26. A rocker member 27, pivoted on the frame of the machine at 28, is provided with a segmental gear rack 27^a which meshes with the pinion 24. An arm 29 is attached to the bevel-gear 21, and connection is made between said arm 29 and the rocker member 27 by an eccentric connecting bar 30, said bar having 30 pivotal connections at 29^a and 30^a. It is obvious, that, with the clutch 25 thrown in, and the gear 21 revolved, the cylinder 3 will be oscillated on its axis, through the medium 35 of the co-action of the connecting rod 30, the rocker 27, and the pinion 24, the gear 21 being driven by gear 22 carried by the vertical main shaft 8.

Provision is made for swinging the 40 wringer horizontally to any position without disturbing the cylinder operating mechanism. This is brought about by the wringer 31 being firmly attached to the housing 5, said housing being adapted to revolve on the 45 stationary bracket 6, with the shaft 8 as an axis. The motor 7 being attached to the shelf 5^a, which is part of the housing 5, is retained in its operative connection with the driving mechanism. Means are provided 50 for locking the housing in three most desirable positions, as best shown in Fig. 3. The said means comprise a vertically movable pin 32 mounted in an extension 6^b of the bracket 6. Said pin is adapted to penetrate 55 cavities 5^c formed in the base of the housing 5. The pin 32 is withdrawn from the cavities 5^c by a lever 33 fulcrumed on the bracket 6 at 33^a, and a spring 34, acting on the pin, forces it into any one of the 60 cavities when the lever 33 is released and a 65

cavity is brought into registration with said pin, thus rendering the locking function automatic.

A friction clutch connection 35 is interposed between the motor 7 and the worm 70 10 as a safe-guard against the burning of the motor, if overloaded.

What I claim and desire to secure by Letters Patent is:

1. In laundry machinery, the combination 75 with a tub and a rotatable cylinder mounted on trunnions in said tub; of a spur pinion mounted on one of the cylinder trunnions; a clutch for connecting said pinion with the trunnion; a segmental rack mounted on the 80 tub and in mesh with said pinion; a rotatable housing mounted above the tub; a stationary bracket with which said housing is connected, said bracket being attached to the tub; a motor connected with said housing; 85 a vertical shaft mounted in said housing and in the stationary bracket; a pair of oppositely disposed bevel gears mounted on said vertical shaft, within the housing; clutch mechanism for connecting said gears, respectively, with said shaft; a bevel gear in mesh with the aforesaid pair of gears; a shaft on which said bevel gear is carried; an operating device provided with a driving element with which said shaft is connected, 90 attached to the housing member; said operating device containing a pair of coacting rotary elements; gear mechanism connecting the motor with the vertical shaft; a third bevel gear carried on the vertical shaft, 95 below the first named pair of bevel gears; a companion gear with which said third gear coacts; a horizontal shaft on which said companion gear is fixed; and an eccentric connecting rod pivotally connected with 100 the said companion gear and the segmental rack mounted on the tub, for driving the cylinder.

2. In laundry machinery, the combination 110 with a tub and a rotatable cylinder mounted on trunnions in said tub; of a spur pinion mounted on one of the cylinder trunnions; a clutch for connecting said pinion with the trunnion; a segmental gear rack fulcrumed on the tub below the cylinder axis, and in 115 mesh with said pinion; a rotatable housing mounted above the tub; a bracket provided therefor; a motor mounted on said housing; a vertical driving shaft journaled in said housing and in the bracket; gear mechanism connecting said shaft and the motor; a bevel gear on said shaft; a companion gear coacting with said bevel gear; a horizontal shaft on which said companion gear is fixed; an eccentric connecting rod pivotally connected 120 with the companion gear and with the segmental gear rack, for driving the cylinder; an operative device attached to the rotatable housing, said device containing a pair of rotary elements; and gear mechanism con- 125 130

necting one of said elements with the vertical driving shaft, for driving said device.

3. In laundry machinery, the combination with a tub and a rotatable cylinder mounted 5 on trunnions in said tub; of a spur pinion mounted on one of the cylinder trunnions; a clutch for connecting said pinion with the trunnion; a segmental gear rack fulcrumed on the tub below the cylinder axis, and in 10 mesh with said pinion; a rotatable housing mounted above the tub; a bracket provided therefor; a motor carried on said housing; a vertical shaft journaled in said housing and in the bracket; gear mechanism connecting 15 said shaft and the motor; a bevel gear on said shaft; a companion gear coacting with said bevel gear; a horizontal shaft journaled in the bracket carrying the companion gear; an eccentric connecting rod 20 connected with an arm provided on the companion gear, and with the segmental gear rack, for driving the cylinder; an operating device attached to the rotatable housing, said operating device containing a pair of 25 rotary elements; gear mechanism connecting one of the rotary elements with the vertical shaft, for driving said element; and clutch mechanism co-acting with the last named gear mechanism, for reversing the operation 30 of the rotary elements.

4. In laundry machinery, the combination with a rotatable cylinder and a support therefor, said cylinder being mounted on trunnions; of a spur pinion mounted on one

of the cylinder trunnions; a clutch for connecting said pinion with the trunnion; a segmental rack fulcrumed on the support, and in mesh with said spur pinion; a stationary bracket attached to the support; a rotatable housing mounted on said bracket; a stop means connected with the bracket and coacting with the rotatable housing for checking the rotation of said housing; a motor connected with the housing; an operating device attached to the housing, said 45 device containing a pair of rotary elements; a bevel pinion connected with one of said rotary elements; a vertical shaft mounted in the housing and in the stationary bracket; a pair of oppositely disposed bevel gears 50 mounted on said vertical shaft, within the housing; clutch mechanism for connecting said gears, respectively with said shaft, the said pair of bevel gears being in mesh with the bevel pinion connected with the rotary 55 element aforesaid; gear mechanism connecting the motor with the vertical shaft; a bevel gear carried on the vertical shaft below the pair of oppositely disposed bevel gears; a bevel gear in mesh with said lower 60 gear; a horizontal shaft which carries the last named bevel gear; and an eccentric connecting rod pivotally connected with the gear on the horizontal shaft and with the segmental rack.

In testimony whereof I affix my signature.

JOHN H. HENDRICKSON.
